(Cl. D83—8)

We claim:

The ornamental design for a bottle holder or similar article, as shown and described.
